UNITED STATES PATENT OFFICE.

BENJAMIN FRANKLIN POTTER, OF ASHTABULA, OHIO.

MOLDING-MACHINE.

No. 802,234.

Specification of Letters Patent.

Patented Oct. 17, 1905.

Application filed March 28, 1905. Serial No. 252,459.

To all whom it may concern:

Be it known that I, BENJAMIN FRANKLIN POTTER, a citizen of the United States, and a resident of Ashtabula, in the county of Ashtabula and State of Ohio, have invented a new and Improved Molding-Machine, of which the following is a full, clear, and exact description.

My invention relates to a molding-machine which is capable of molding articles of many characters and can be used with plastic materials of various kinds. It is especially applicable, however, to the molding of hollow building-blocks of concrete and the like.

The principal objects of the invention are to provide means for simultaneously introducing material into a mold and tamping it therein, to provide an efficient arrangement for continuing the tamping operation from

one end of the mold to the other without diminishing the length of the strokes of the tamping device, to provide an efficient arrangement for drawing cores and the like from the mold, to provide for conveniently

removing the molded article after the molding operation is completed, to provide for cutting the material in the mold from that in the feed-box when the mold is filled, and to generally increase the efficiency without complicating the structure of machines of this character.

Further objects of the invention will appear in the course of the subjoined description.

Reference is to be had to the accompanying drawings, forming a part of this specification, in which similar characters of reference indicate corresponding parts in all the figures.

Figure 1 is a side elevation of a molding-machine for making building-blocks constructed in accordance with the principle of my invention. Fig. 2 is a sectional view on the line 2 2 of Fig. 1. Fig. 3 is a fragmentary sectional view on the line 3 3 of Fig. 1.

Fig. 4 is a central longitudinal section of a portion of the device. Fig. 5 is a sectional view on the line 5 5 of Fig. 1. Fig. 6 is a sectional view on the line 6 6 of Fig. 1, and Fig. 7 is a perspective view of a building-block which can be made on this machine.

The machine illustrated in the drawings is mounted upon a stationary base 11, which is provided with rollers 12 and with guides 13 for tracks 14. These tracks are designed to

support a frame 15, upon which is mounted 55 a feed-box 16, having a hopper 17, an open end 18, and a longitudinal central guide 19. The plunger 20 for tamping the material is bifurcated, and its two portions are provided with feet 21, located within the feeder-box, 60 the body of the plunger passing through openings 22 in the front end of the feed-box. This plunger is guided upon opposite sides of the guide 19 and is designed to pass through the open end 18 of the feed-box in a manner to 65 be described. It may be operated by an engine or by hand, and for convenience I have illustrated as a means for moving the plunger a lever 23, pivotally connected with the plunger through a rod 24 and pivoted at the 70 point 25 to a stationary support 26. If an engine is used, it is mounted in a stationary position.

The plunger when forced through the open end 18 is designed to pass into a mold located 75 adjacent to this end of the feed-box. This mold is provided with a bottom plate 27, pivotally mounted upon a rod 28 and provided with a front plate 29, rigidly mounted with respect to the bottom and having handles 30 80 for operating it about the rod 28. It is also provided with a back plate 31, which may have a face 32 of any desired configuration— as, for example, a roughened rock surface or the like. This plate is located upon an arm 85 33, pivoted upon a rod 34. The mold has a top plate 35, which is movably mounted on and operated by a screw 36, having a hand-wheel 37. This screw has a bearing in a plate 38, which is mounted in a stationary position 90 with respect to the frame 15. The front and back side plates are designed to be held in closed position by means of sliding latches 39, operated by pivoted levers 40. The mold also has a sliding end 41, operated by a screw 42 95 and hand-wheel 43, the screw having screw-threaded engagement with a stationary portion of the frame. The other end of the mold is designed to be closed by a plate 44, having slots 45 for the passage of the feet 31 of the 100 plunger. This plate is operated by a lever 46, to which it is pivoted, the lever being in turn pivoted upon a stationary part of the frame 15 and having a handle or treadle 47. Upon this plate is mounted a core-piece 48, which 105 is designed to form a depression in the end of the block. This core-piece moves with the plate and by the operation of the lever 46.

When the plate and core-piece are in the position shown in Fig. 4, the plunger can pass through the perforations 45 and operate in the mold in the desired manner. On the opposite end of the mold a core-piece 49 is preferably located, and this is operated by a lever 50, having a handle or treadle 51, both of these levers being pivoted upon a shaft 52. Upon the same shaft another lever 53 is pivoted. This lever has a handle or treadle 54 and is connected with a core-plate 55, operating in a guide 56. A core 57 is mounted upon the core-plate and is designed to pass through an opening 58 in the bottom of the mold. The core may be bifurcated or have as many projections as may be desired to produce the requisite number of openings in the article to be molded.

Upon the base 11 is a standard 59, having a screw 60, provided with a hand-wheel 61 and designed to engage in a screw-threaded boss 62 on the frame 15 for operating the frame back and forth. The purpose of making the frame movable is to provide for the same kind of tamping of the molded article irrespective of the amount of material in the mold. It will be seen that with a stationary operating means for the plunger the filling of the mold would result in forcing the plunger to take a shorter stroke, and consequently the tamping of the material would vary from one end of the mold to the other. With the arrangement shown or any other which is the equivalent thereof the frame can be moved back as the mold fills, and consequently the plunger may be given its full stroke at all times and the material will be tamped with equal density in all parts of the mold.

When the mold is filled through the operation of the plunger and tamped by the same operation, the core-pieces 48, 49, and 57 are withdrawn by the operation of the levers with which they are connected, and the plate 44 is also withdrawn to cut the block from the material in the feed-box. The cover is then loosened and the rock-faced side swung away from the molded block after the latches 39 on that side are released. The plunger having been removed at the time when the block is completed, the bottom and side connected therewith can be swung over upon the pivot 28 and the block will be found resting upon the side 29 at the side of the machine and can then be readily removed to the drying-kilns or other desired place for curing. By the operation of the machine in this manner it is found that blocks can be molded with much more uniform density and that they will consequently last much longer in use. It is also found that they can be produced at a rapid rate and that for the production of various kinds of blocks or other molded articles it is merely necessary to change the respective parts of the mold, the operation being the same for all kinds. Also the various

molding materials may be operated upon in this machine, and it is not limited in its usefulness to any particular kind of molding.

While I have illustrated and described a particular form in which my invention may be embodied, it will be readily understood that it can be carried out in many other ways within the scope of the claims.

Having thus described my invention, I claim as new and desire to secure by Letters Patent—

1. A molding-machine comprising a series of rollers, movable tracks mounted thereon, a frame connected with said tracks and adapted to support a mold, a stationary support, and means for moving the plunger connected with said support. 75

2. A molding-machine comprising a series of rollers, movable tracks mounted thereon, a frame connected with said tracks and adapted to support a mold, a stationary support, 85 means for moving the plunger connected with said support, and means for moving the tracks and frame on the rollers.

3. A molding-machine comprising a series of rollers, movable tracks mounted thereon, 90 a frame connected with said tracks and adapted to support a mold, a stationary support, means for moving the plunger connected with said support, a feed-box mounted upon the frame in which the plunger is designed to operate, and a mold mounted adjacent to said feed-box. 95

4. A molding-machine comprising a movable frame, a mold thereon, a feed-box having an open end located adjacent to said mold and 100 provided with a longitudinal guide, a bifurcated plunger located in the feed-box on opposite sides of said guide, a stationary support, and means on said support for moving the plunger through the feed-box. 105

5. A molding-machine, comprising a feed-box having a guide therein and provided with an open end, and a plunger in the feed-box adapted to work through the open end, to pass on both sides of the guide and to be guided 110 by said guide.

6. A molding-machine comprising a feed-box having a longitudinal guide therein and provided with an open end, and a bifurcated plunger in the feed - box adapted to work 115 through the open end, the two portions of said plunger being located upon opposite sides of said guide.

7. A molding-machine comprising a feed-box having an open end, a mold having an open end located adjacent to the open end of the feed-box, a plunger in the feed-box adapted to pass through the open ends of the feed-box and into the mold, and a plate constituting a closure for the open end of the mold and provided with perforations for the reception of said plunger. 120

8. A molding-machine comprising a feed-box having an open end, a mold having an open end located adjacent to the open end of the 130

feed-box, a plunger in the feed-box adapted to pass through the open ends of the feed-box and mold into the mold, a plate constituting a closure for the open end of the mold and provided with perforations for the reception of said plunger, and means for moving said plate across the space between the mold and feed-box.

9. A molding-machine comprising a feed-box having an open end, a mold having an open end located adjacent to the open end of the feed-box, a plunger in the feed-box adapted to pass through the open ends of the feed-box and mold into the mold, a plate constituting a closure for the open end of the mold and provided with perforations for the reception of said plunger, and means for moving said plate across the space between the mold and feed-box; said means comprising a lever pivotally mounted upon the molding-machine and pivotally connected with said plate.

10. A molding-machine comprising a feed-box having an open end, a mold having an open end located adjacent to the open end of the feed-box, a plunger in the feed-box adapted to pass through the open ends of the feed-box and mold into the mold, a plate constituting a closure for the open end of the mold and provided with perforations for the reception of said plunger, and a core-piece rigidly mounted with respect to said plate and located in the center thereof.

11. A molding-machine comprising a feed-box, a mold located adjacent thereto, a plunger in the feed-box adapted to enter the mold, a plate movable between the mold and feed-box and having perforations for the reception

of the plunger, a core-piece on the plate, a second core-piece at the opposite end of the mold, and a movable core within the mold.

40

12. A molding-machine comprising a feed-box, a mold located adjacent thereto, a plunger in the feed-box adapted to enter the mold, a plate movable between the mold and feed-box and having perforations for the reception of the plunger, a core-piece on the plate, a second core-piece at the opposite end of the mold, and a movable core within the mold; each of said cores and core-pieces being provided with a lever pivotally mounted upon a shaft located on the machine for operating the cores and core-pieces and withdrawing them from the mold.

45

13. A molding-machine comprising a mold having an end piece movable transverse to the longitudinal direction of the mold, an end piece on the opposite end movable in a direction parallel to the longitudinal direction of the mold, and a top plate movable away from the main body of the mold.

50

14. A molding-machine having two end plates, one movable in one direction and the other in a direction at right angles thereto, said mold also having two side plates movable in a curved path away from the body of the mold.

55

In testimony whereof I have signed my name to this specification in the presence of two subscribing witnesses.
